UNITED STATES PATENT OFFICE.

HARRY G. VAN ORNUM, OF PIERCEFIELD, NEW YORK.

SLICE FOR PAPER-MAKING MACHINES.

1,261,194.

Specification of Letters Patent. Patented Apr. 2, 1918.

Application filed July 25, 1917. Serial No. 182,697.

To all whom it may concern:

Be it known that I, HARRY G. VAN ORNUM, a citizen of the United States, residing at Piercefield, in the county of St. Lawrence, State of New York, have invented certain new and useful Improvements in Slices for Paper-Making Machines; and I do hereby declare the following to be a full, clear, and exact description of the invention, such as will enable others skilled in the art to which it appertains to make and use the same.

This invention relates to paper making machines, and has particular reference to improvements in slices for Fourdrinier machines.

The object of the invention is to provide an improved form of slice in paper making machines by means of which the distance between the apron which delivers the pulp or stock to the wire fabric of a Fourdrinier machine may be varied in proportion to the distance between the lower edge of the slice, as the latter distance is varied in making adjustments for papers of different character.

In all those paper making machines which are known to me, the slice has consisted merely of a transverse plate which is vertically adjustable between the deckel rails by means of adjusting screws which must be manually set. There has, therefore, been no provision made for varying the longitudinal position as well as the vertical position of the slice plate.

By reason of the improved construction of my invention, I am enabled to make a more perfect adjustment of the machine for making papers of all grades, that is, in changing the machine from the position where it made light weight paper to a heavy weight adjustment, and vice versa. The invention is also valuable in obviating the necessity of supplying water to the stock as is often the case when the stock runs too "free", thereby causing breaks in the sheet from lumps which clog the head box and are associated therewith as the water is added. Thus, by reason of my improved mechanism, instead of varying the quantity of water which passes out with the stock, I vary the rapidity with which the water is drained from the stock, in order to overcome the extremes of "too slow" or "too free" stock. More particularly, I have provided a slice which is movable toward and away from the

feeding end of the apron, so that the area of the screen or Fourdrinier wire which is exposed between the end of the apron and the slice determines a preliminary screening space through which the water may drain from the stock which is still in the "pond" behind the slice before it progresses below the latter on its way to the suction boxes. And, by varying the relative position of the slice longitudinally with respect to the forward or feeding end of the apron, in proportion to the varying adjustment of the slice, I make it possible to maintain depth of the pond substantially constant with a constant feed of the water through the head box.

With the above objects in view, and such others relating to the details of construction, as may hereinafter appear, my invention will now be fully set forth and described, reference being had to the accompanying drawings.

In the drawings:—

Figure 1 is a plan view of the stock feeding end of the machine,

Fig. 2 is a side elevation thereof,

Fig. 3 is a longitudinal section therethrough.

Fig. 4 is a section on line 4—4 of Fig. 2.

Fig. 5 is an enlarged elevation of a part of the adjusting mechanism, and

Fig. 6 is a detail of the apron construction.

Referring more particularly to the drawings, 1 represents the top of the frame of a Fourdrinier paper-making machine over which the Fourdrinier wire 2 is operated. The usual deckel frame 3 carries the pulleys 4 over which the deckel straps 5 a run, the sides of the frame 3 being connected by means of the shafts 6 through whose instrumentality the sides of the frame are adjusted with relation to the upper run of the Fourdrinier wire 2. Also, the shafts 6 are geared to a longitudinal shaft 7, so that when one of the shafts 6 is operated by means of the hand crank 8, the other will be simultaneously and correspondingly turned.

The pulp is fed to the machine over the apron 9 from whose edges the sideboards 10 rise, the apron being mounted upon an apron board 11.

A slice 12 is suspended between the deckel frame 3, and is vertically adjusted by means of the adjusting screws 13. Furthermore, the slice 12 is formed in extensible sections which permit the slice to be accommodated

to the various transverse adjustments of the deckel frames.

The slice 12 has its ends mounted in blocks 14 which are carried by the deckel frames, 5 vertical guides 15 are formed in the blocks upon the inside of the frames receiving said ends in slidable relation in turn, the blocks 14 are longitudinally slidable in slots 16 formed in the deckel frames. Furthermore, 10 the ends of the set screws or adjusting screws 13 bear upon inclined faces 17 formed in the upper edge of the deckel frames, their inclination being such that as the slice is raised upon the inclines, its movement is toward 15 the end of the apron 9. The major portions of the blocks 14 lie outside of the frames 3 and are longitudinally threaded to receive the threaded shafts 18. The shafts 18 are provided upon their rear ends, with 20 the bevel gears 18' which mesh with corresponding gears 19 mounted on shafts 20. The shafts 20 have bearings in the frames 3, and between the latter extend into a hollow shaft 21, wherein they are adjustably 25 secured by means of the set screws 22. Thereby, the shafts 20 may be extended or contracted in accordance with the adjustment of the deckel frames.

In the use of the slice constructed in accordance with the foregoing description, the slice is given a two-fold movement, one toward and away from the end of the apron, and the other vertically toward and away from the screen. As the slice is moved away 35 from the forward end of the apron it is necessary to guard the pulp in the pond from passing out from under the sides of the deckel frame, and for this purpose the guards 23 are secured to the blocks 14, said 40 guards consisting of sheet metal plates whose height corresponds to the height of the side plates 10 of the apron, and which constitute extensions of the latter so as to inclose the sides of the pond at all times. Fourdrinier 45 machines may be used for the manufacture of all grades and weights of paper, according to the adjustment of the slice, the position of the slice determining the depth of the pond of pulp upon the apron preparatory 50 to feeding it upon the screens. Therefore, since the slice, in former constructions, must be kept at a given vertical height in order to maintain the certain depth of the pond, it has been necessary to add water to 55 the stock in order to maintain the proper consistency of the latter. By the new construction, however, it is possible to adjust the slice in order to vary the consistency of the stock and still maintain the proper depth 60 of the pond, and to do this without moving from side to side of the machine. Thus, when the slice is positioned at the forward end of the apron, and stands at a certain previously 65 adjusted distance above the Fourdrinier wire, the material will flow there-

under at a certain weight dependent upon the consistency of the material and the size of the opening. Then, if the stock is too wet, the slice may be adjusted away from the apron so that more water will leave the stock through the Fourdrinier wire before passing below the slice. However, simultaneously with the forward adjustment of the slice, it is lowered, so as to reduce the size of the opening below the evener edge 75 of the slice. By this means the depth of the pond may be maintained while the consistency of the material which passes onto the Fourdrinier wire is varied. When the paper fibers are short, that is when the stock is "slow", it tends to hold more water than when the fibers are long or the stock is "free" and in this condition a sufficient amount of water does not drop below the wire as the material makes its way to the 85 suction boxes so that the latter are overburdened. Therefore, the two-fold adjustment of the slice will permit a compensation for this purpose without the necessity of adding water to the stock in order to provide a sufficient initial quantity to screen with before reaching the apron. In making newspapers and other papers of light weight, it often happens that when the stock runs too slow 90 it is necessary to cut off the water, and then 95 later to "free up" the stock, a process which causes lumps or masses of the pulp to leave the flow boxes which, crowded below the slice, causes lumps and breaks in the paper. This disadvantage is also avoided by the 100 use of my improved construction.

What I claim as my invention is:—

1. A slice for paper-making machines, comprising in combination with the deckel frames thereof, a slice structure adjustable 105 vertically and horizontally with relation to the deckel frames and a means for effecting the adjustment by a unitary action.

2. A slice for paper-making machines, comprising in combination with the deckel frames thereof, a slice structure adjustable 110 vertically and horizontally with relation to the deckel frames, and means for accomplishing the vertical adjustment as a result of a horizontal adjustment.

3. In a paper-making machine, the combination with the deckel frames and apron thereof, of a slice simultaneously adjustable away from the apron and toward the bottom 115 of the frames, and means for accomplishing one adjustment as a result of the other.

4. In a paper-making machine, the combination with the deckel frames, of a slice, blocks longitudinally slidable in the deckel frames, vertical guides slidably carrying the 120 slice, means for changing the vertical position of the slice in said slidable ways as the blocks are longitudinally moved, and means for moving the blocks.

5. In a paper-making machine, the com- 130

5 combination with the deckel frames, of a slice, blocks longitudinally slidable in the deckel frames, vertical guides slidably carrying the slice, cam surfaces formed on the deckel frames, means carried by the slice in operative engagement with said cam surfaces, and means for moving the blocks longitudinally, longitudinal movement of the blocks causing a relative change in the vertical 10 position of the slice.

15 6. A slice for paper making machines, comprising in combination with the deckel frames thereof, a slice structure adjustable vertically and horizontally with relation to the deckel frames, and means for accomplishing one adjustment as a result of the other.

20 7. In a paper making machine, the combination with the deckel frame and apron therefor, of a slice simultaneously adjust-

able away from the apron, and toward the bottom of the frame, and means for accomplishing the vertical adjustment as a result of the horizontal adjustment.

25 8. In a paper making machine, the combination with the deckel frames, of a slice, blocks longitudinally slidable in the deckel frames, vertical guides slidably carrying the slice, means for changing the vertical position of the slice in said slidable ways as the 30 blocks are longitudinally moved, and means for moving the blocks, said block moving means being simultaneously operative on both sides of the machine.

35 In testimony whereof I affix my signature in the presence of two witnesses.
